Primary Examiner — Prabhakar Deshmukh*Assistant Examiner* — Holly E Thurman(74) *Attorney, Agent, or Firm* — Lippincott Burnett LLP; Paul Burnett(57) **CLAIM**

The ornamental design for a decorative microphone, as shown and described.

DESCRIPTION

FIG. 1 is a perspective view of a decorative microphone showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The design is directed to the ornamentation applied to the decorative microphone. The hinge and fastener (depicted as a hinge, coupled using a screw, bolt, nut and washers), and the covering of the internal mechanism for the decorative microphone (depicted as broken lines within the openings on the sides and back of the decorative microphone) are shown in broken lines. The broken lines form no part of the claimed design.
